UNITED STATES PATENT OFFICE.

HALVOR A. LUND, OF LOS ANGELES, CALIFORNIA.

CHANGEABLE, MULTIFACE SIGN.

Application filed August 3, 1925. Serial No. 47,819.

This invention relates to signboards and especially to large area signboards and carrying a high efficiency of advertising value and, therefore, being let or engaged at 5 a good rental figure.

Such boards bear expensive posters or have the media hand painted on them at the site of the board. The latter practice, of course, involves a dead loss of time in the 10 artist's transit to and from the various sites of the different sign boards.

The present invention has for its objects to greatly increase the rental value of signboards; to provide for the preparation of 15 the sign media at a central plant or studio, and to eliminate travel of artists and supplies from board to board. Another object is to enhance the attractive effect of the 20 board by inducing and holding the notice of the public by reason of a visible change of sign from time to time.

Numerous other objects and advantages will be made manifest in the following specification of an embodiment of the invention shown in the annexed drawings; it being understood that modifications, variations and adaptations may be resorted to within the spirit and scope of the invention 25 as it is here claimed.

Figure 1 is a front elevation of the signboard.

Figure 2 is a section and plan of parts.

Figure 3 is a section and elevation of the sign operating mechanism.

Figure 4 is a section and plan showing a brake.

Figure 5 is a cross-section of the shift bar and its cam track.

Figure 6 is a detail showing the assembly 40 of a sign unit on its bearings.

The invention is here incorporated in a sign structure including a frame having end columns 2 with top lamps 3, and a ridge device 4 and a bottom rail 6, spaced to receive 45 a set of sign units 5. The units comprise, each, an element of triangular cross-section of a width and length of face which will differ in various sign boards. These units are adapted to be mounted in axial bearing so 50 that they may be rotated, in the present case on vertical axes, though they may be otherwise disposed.

A unit may be of various forms of construction and material. As here shown the 55 unit is hollow and has at its upper end a socket 7 to be slipped up on a bearing pin 8

in a beam 9 forming a part of the ridge 4. The beam may be covered by a water shedding strip 10 having draining eaves 11 forming a lateral cover for the top ends of the row of units 5. The lower end of each unit has a stud or trunnion 12 whose lower portion is non-circular, as triangular at 13 to mesh in and turn with a socket-shaft 15 into the upper end of which it may be dropped 60 after the top end of the unit has been slid up on the top support 8.

The several pairs of hearings 8-15 are so spaced in a plane that when a given series of 70 the units 5 has been installed and the units are all arranged with a side face F of each lying in a common plane, their front edges, in said plane, will nearly meet.

In other words a signboard front is presented which is formed of a number of equal 75 sections; each section being movable. Each unit has three of these signboard sections, and, therefore, three different signs are presentable, in succession at the front of the signboard.

Having provided triangular sign-section units evenly disposed in a plane and rotative on coplanar axes, means are provided for concurrently turning all of the units in one direction a part of a revolution, namely, one 80 third of a turn so as to bring into view successively the three faces F of each unit, and to provide for a period of rest to enable reading the advertising media.

While various forms of intermittent action 90 turning means may be employed, a simple, economical, substantial and practical form is here shown. Each lower socket-shaft 15 is supported in a bearing 16 and has a disc 17 with three equispaced, perpendicular pins 18 95 so arranged as to the socket hole that the units 5 can be positioned only in a predetermined manner in the sockets. The pins 18 are adapted to be successively engaged by a draw-bar 20 having a set of lateral 100 hooks 21 spaced to correspond with the spacing of the centers of the units 5.

The draw-bar 20 is reciprocated by suitable means, as a link 22 attached to a crank 23 on a gear 24 geared down from a motor 105 25. When the draw-bar pulls in one direction it comes into contact with a near pin 18 of each disc 17 and then all of the discs are turned together. Since the pins 18 move in an arc, I provide cam-tracks 26 having 110 similar arc-slots 27 into which project pins 28 on the ends of the bar 20. This gives the

bar an orbit for a part of its stroke similar to the path of each pin 18. When the draw-bar moves back it follows the arc-slots 27 for a short distance and then runs onto switches 29 which deflect the bar-pins 28 until the hooks 21 clear of and apposed to the near unit turning pins 18 lying in a row at the front. Then the bar-pins engage cam-walls 30 and slide in past the switches 29, which are yieldable in one direction. This brings the bar-hooks 21 over into effective position on the forward stroke.

To prevent fluttering and looseness of the units each disc 17 is engaged by a brake 32 which steadies action and prevents movement of the units by wind pressure. Each brake has a lug 33 to position the unit as a hook 21 pulls a pin 18 around.

The bar 20 is free to float to and fro under top bearings 34 holding it down flat to position the cam-pins 28.

It will be seen that the several faces F of each unit 5 may be painted or otherwise applied with the several subjects of advertisement at a central plant or studio and then transported and easily and quickly installed in a signboard in their proper co-relation to cooperate, in given set of faces F, to show the sign media.

The actuating mechanism is a fixture in each signboard and requires only occasional inspection and oiling.

The panels may be translucent and interiorly illuminated if desired by lamps L.

It will be seen that each face F of each unit 5 is a section of a group which bears a full signboard display media.

What is claimed is:

1. In a device of the class described, a set of signboard units each having a plurality of media faces and being rotative to successively present different faces in a common front plane, and including a reciprocating, cam controlled, actuating bar, means for concurrently turning all of the units in one direction a predetermined degree and upper and

lower bearing means providing for quick bodily mounting and dismounting of each unit for replacement of sets of units independently of the operating means and a switch means cooperative with the bar and forming a guide during its stroke in one direction.

2. A signboard including rotative units each having a plurality of sign faces, and means for concurrently turning the units in one direction to change sign faces and effect rest periods; said means including fixed cam tracks, each having a switch gate, a reciprocating bar operative on one stroke to actuate said units and being thrown by said switches to ineffective position on the return stroke.

3. A signboard including rotative units each having a plurality of media bearing faces, and driving couplings for concurrently turning all of the units to change the display front and to provide for a period of rest to enable reading the media said units being detachably combined with the couplings, a reciprocating bar, and means for causing the bar to shift in an orbital path to engage and disengage from the driving couplings.

4. A signboard including a set of units each having sign media faces movable in predetermined sign groups into a front display position edge to edge, rotative, driving supports on which the units are removably stepped, and a cam shifted reciprocating draw-bar engaging and disengaging said supports to turn them together.

5. A signboard including a set of units which have, each, multiple sign faces adapted to lie edge to edge in selected front display groups, supports on which the units are mounted, a reciprocating draw-bar to actuate the units together, and cam-track means for causing the bar to move toward and from effective relation to the said supports.
